UNITED STATES PATENT OFFICE.

GEORGE G. FLOYD, OF ST. LOUIS, MISSOURI, ASSIGNOR TO THE SHICKLE,
HARRISON & HOWARD IRON COMPANY, OF SAME PLACE.

DESIGN FOR A BODY-BOLSTER.

SPECIFICATION forming part of Design No. 32,504, dated April 10, 1900.

Application filed March 14, 1900. Serial No. 8,680. Term of patent 14 years.

To all whom it may concern:

Be it known that I, GEORGE G. FLOYD, a citizen of the United States, residing at the city of St. Louis, in the State of Missouri, have 5 invented and produced a new and original Design for Body-Bolsters, of which the following is a specification, reference being had to the accompanying drawings, forming part thereof.

Figure I is a plan view of a body-bolster, showing my design. Fig. II is a side elevation.

As shown in the drawings, the leading or material feature of my design consists in a 15 body A, having notched or cut-away portions B at its ends, from which the upper surface

of the body extends inwardly and downwardly for a distance and then horizontally to the center. The lower surface of the bolster extends on inwardly and downwardly 20 projecting lines E for a distance and then on horizontal or substantially-horizontal lines F and G to the middle of the bolster, where the body has a downwardly-extending projection I.

I claim as my invention—
The design for a body-bolster as herein shown and described.

GEORGE G. FLOYD.

In presence of—

HUGH M. CLARE,
GEO. K. STOBLITZELLE.
